UNITED STATES PATENT OFFICE.

HENSON DAVIS, OF ROUNDUP, MONTANA.

LAMP HOLDER FOR MINERS' CAPS.

Application filed December 22, 1919. Serial No. 346,447.

To all whom it may concern:

Be it known that I, HENSON DAVIS, a citizen of the United States, residing at Roundup, in the county of Musselshell and 5 State of Montana, have invented new and useful Improvements in Lamp Holders for Miners' Caps, of which the following is a specification.

This invention relates to means for connecting a lamp to a cap and the principal 10 object of the invention is to provide means for securely holding the lamp in place on the cap so that there is no danger of the lamp becoming detached when the miner 15 moves about.

Another object of the invention is to provide means whereby the lamp may be easily and quickly placed in position on the cap.

This invention also consists in certain 20 other features of construction and in the combination and arrangement of the several parts, to be hereinafter fully described, illustrated in the accompanying drawings and specifically pointed out in the appended 25 claims.

In describing my invention in detail, reference will be had to the accompanying drawings wherein like characters denote like or corresponding parts throughout the 30 several views, and in which:—

Figure 1 is a perspective view of the invention.

Figure 2 is a sectional view of the attaching means alone.

Figure 3 is a detail perspective view of a 35 portion of a miner's lamp showing attaching hooks thereon.

In these views 1 indicates the cap which is provided with a long vizor 2 of stiff material. 3 indicates a bracket or holder of substantially Z-shape with one member riveted to the vizor and its other member connected with the top of the cap. The intermediate member lies parallel with the front 40 of the cap. A plate 4 of spring metal has its lower part connected with the lower part of the holder member by rivets or the like and the upper part of this plate is reduced with its extremity of V-shape. This upper 45 part is bent over at right angles and secured to the top member of the bracket. The junction of the intermediate part of the bracket with the upper part forms a bead 5 which projects outwardly slightly so as to 50 space the plate 4 from said intermediate part. The edges of said plate, adjacent the

beginning of the reduced part, are curved outwardly as at 6 to form directing wings to guide the hooks 7 on the lamp 8 between the plate and the intermediate part of the 60 bracket. The bent over part of the plate is provided with a hole 9 which is continued through the upper part of the bracket and the edges of the extremity of said plate are bent upwardly to provide guiding ribs 10 65 to guide the upper hook 11 of the lamp to said hole. A slot 12 is formed in the bent over part of the plate and the bead. This slot receives the part of the upper hook which is soldered to the lamp. A hole 13 70 may be formed in the plate to increase its flexibility. As will be seen the lamp is provided with the two side hooks and the upper hook, the upper hook engaging the hole 9 and the side hooks engaging the edges of the 75 plate, said side hooks being guided into position by the outwardly bent portions of said plate. In this way the lamp is held at three points.

What I claim is:

1. A device of the class described comprising a lamp having a pair of side hooks and an upper hook, a substantially Z-shaped cap bracket and a spring plate having its lower part secured to the lower member of the bracket and its upper part reduced and having its extremity bent at right angles and secured to the top member of said bracket, the junction of the intermediate part of the bracket with the upper part forming a bead which projects outwardly so as to space the plate from said intermediate part and the edges of said plate adjacent the beginning of the reduced part being curved outwardly to form directing wings to guide the hooks on the lamp between the plate and the intermediate part of the bracket, the bent over part of the plate being provided with a hole which is continued through the upper part of the bracket and the edges of said plate being bent upwardly to provide guiding ribs to guide the upper hook of the lamp to said hole.

2. A device of the class described comprising a cap having a long vizor of stiff material formed thereon, a substantially Z-shaped bracket having one member riveted to the vizor and the other member connected with the top of the cap, an intermediate 105 member lying parallel with the front of the cap and a spring metal plate having its

lower part connected with the lower part of the bracket member by means of rivets, the upper part of said plate having a reduced portion with its extremity of V-shape formation, the upper part being bent over at right angles and secured to the top member of the bracket, the junction of the intermediate part of the bracket with the plate forming a V which projects outwardly to space said plate from said intermediate part, the edges of said plate adjacent the

beginning of the reduced part being curved outwardly to form guiding wings, a lamp centrally arranged on said bracket, side and upper hooks provided on said lamp and said upper hook being adapted to engage a hole formed in said plate and said side hooks adapted to engage the edges of the plate and be guided into position by the outwardly bent portions of said plate. 15 20

In testimony whereof I affix my signature.
HENSON DAVIS.
